Nike KD Elite Basketball Shorts, Announced Jun. 27, 2017 [Site Visited Aug. 30, 2017] <http://sportfits.com/nike-kd-elite-basketball-shorts/>.*

Primary Examiner — Karen E Kearney*Assistant Examiner* — Amy C Wierenga(74) Attorney, Agent, or Firm — Banner & Witcoff, Ltd.(57) CLAIM

The ornamental design for a shorts, as shown and described.

DESCRIPTION

FIG. 1 is a front perspective view of a shorts showing my new design;

FIG. 2 is a rear perspective view thereof;

FIG. 3 is a front view thereof;

FIG. 4 is a rear view thereof; and,

FIG. 5 is a right side view thereof.

The even-length broken lines within the shaded area represent environmental stitching and forms no part of the claimed design. The uneven-length broken lines immediately adjacent to the shaded area define the bounds of the claimed design and form no part thereof. The uneven-length broken lines showing the remainder of the shorts represent environmental subject matter and form no part of the claimed design.
